UNITED STATES PATENT OFFICE.

MARCELLUS W. MEEK, OF ARCADIA, CALIFORNIA.

FUR-PELT STRETCHER.

Application filed December 31, 1925. Serial No. 78,527.

My invention relates to a combined holder and stretcher for the pelts of fur-bearing animals and particularly the smaller varieties of animals, for instance, rabbits, foxes, 5 minks, and the like, the principal objects of my invention being to generally improve upon and simplify the construction of the existing forms of fur or pelt stretchers and to provide a device of the character referred to that will tend to exert constant pressure 10 in stretching the fur or pelt and said device being constructed so as to effectually prevent the pelt or fur from contracting lengthwise during the fur stretching and drying operations. 15

Further objects of my invention are to provide a fur stretcher that is relatively simple in construction and which is capable of being easily and cheaply produced.

With the foregoing and other objects in view, my invention consists in certain novel features of construction and arrangement of parts that will hereinafter be more fully described and claimed and illustrated in the 25 accompanying drawings, in which—

Fig. 1 is an elevational view of a fur stretcher constructed in accordance with my invention.

Fig. 2 is an edge view of the stretcher.

The fur stretcher contemplated by my invention is formed from a single section of wire having a certain degree of resiliency and the central portion of the wire section is bent to form a coil spring 10 and which has at least two or three convolutions. From the sides of this coil the wire is extended in parallel tangential lines to form short legs 11 and from the ends of the latter the wire is bent outwardly to form short shoulder portions 12 that occupy positions approximately at right angles to the planes occupied by the legs 11. From the outer ends of the shoulder portions 12 the wire extends in planes that are approximately parallel with the planes occupied by the legs 11 to form a pair of elongated legs or arms 13 which serve as a support for the fur or pelt that is stretched.

The terminal portions of these legs or 50 arms 13 are bent slightly outward away from each other and sharpened to form points or prongs 14 and the portions of the legs or arms adjacent to said terminal points are bent into corrugated form as designated by 55 15.

Under normal conditions or while the

stretcher is not in use the arms or legs 13 are spread apart as illustrated by solid lines in Fig. 1 and when the stretcher is applied to a pelt the arms or legs are drawn inwardly 60 toward each other in order that the device may be readily inserted lengthwise through the pelt and with the coil 10 and legs 11 projecting through an opening at the head or neck portion of the pelt. 65

The contracted or shoulder portions of the pelt bear directly upon the shoulder members 12 of the stretcher and, where the pelt is of sufficient length, after being stretched lengthwise on the device the lower or rear 70 end of the pelt is engaged on the prongs 14 and thus the pelt or skin is effectually retained in stretched condition on the device.

If the pelt or skin is not long enough to be engaged at its lower end upon the prongs 75 14, the lower portion of said skin or pelt will be engaged by the corrugations 15 on the lower portions of the arms or legs 13 and as the pelt or skin dries it will be held by said corrugations against contracting length- 80 wise.

While the stretcher is in use the resiliency of the spring portion 10 tends to spread the arms or legs 13 apart and as a result the supported skin or pelt will be effectually 85 stretched.

Thus it will be seen that I have provided a relatively simple, practical and easily applied fur or pelt stretcher, the same being constructed so as to effectually prevent the 90 skin or pelt from contracting lengthwise during the drying and stretching period.

It will be understood that minor changes in the size, form and construction of the various parts of my improved fur pelt stretcher may be made and substituted for those herein shown and described without departing from the spirit of my invention, the scope of which is set forth in the appended claims.

I claim as my invention:

1. A fur stretcher composed of a section of wire, the central portion of which is bent to form a coil, portions of the wire adjacent to said coil being bent outward away from each other to form abrupt pelt-supporting shoulders, the portions of wire between said shoulders and the ends of the section of wire constituting pelt-supporting arms, the ends of which are pointed and portions of which arms adjacent to said pointed ends are corrugated. 105

2. A fur stretcher composed of a section

of wire, the central portion of which is bent to form a coil, portions of the wire immediately adjacent to said coil being extended in the same direction to form short parallel legs, portions of the wire adjacent to said legs being bent outwardly away from each other so as to form abrupt pelt-supporting shoulders, the remaining portions of the sec-

tion of wire extending from the outer ends of said shoulder in substantially straight lines to form elongated pelt-supporting arms, the ends of which are pointed and portions of which arms adjacent to said pointed ends are corrugated.

In testimony whereof I affix my signature.
MARCELLUS W. MEEK.
